CIRCULATING COOLING SYSTEM FOR
INTERNAL COMBUSTION ENGINESThomas B. Chace, Chicago, Ill., assignor to The
Dole Valve Company, Chicago, Ill., a corpora-
tion of Illinois

Application November 9, 1934, Serial No. 752,256

4 Claims. (Cl. 123—178)

This invention relates to circulating cooling systems for internal combustion engines and has for its object to provide a new and improved system of this description. The invention has as a further object to provide a circulating cooling system for internal combustion engines, whereby there is an improved construction of bypass for directing the liquid around the radiator. The invention has as a further object to provide a cooling system for internal combustion engines wherein there is a valveless bypass for directing the liquid around the radiator so that it will not go through such radiator, said bypass being rendered ineffective of a Venturi action of the liquid at its upper end. The invention has further objects which are more particularly pointed out in the accompanying description.

Referring now to the drawings,

Fig. 1 is a view showing a circulating system embodying one form of invention;

Fig. 2 is an enlarged view of the thermostatic valve construction;

Fig. 3 is a view showing a modified construction of the lower end of the bypass;

Fig. 4 is a view showing a modified construction.

Like numerals refer to like parts throughout the several figures.

In the construction I have shown the device as applicable to an automobile, but it is of course evident it may be applied to any internal combustion engine. In this construction there is a radiator A and an internal combustion engine having a water jacket B having a connection leading from the water jacket to the radiator, a part of which connection is formed by a hose section C. In the particular construction shown this connection includes a bracket member D for easy attachment to the radiator.

Some suitable valve device is arranged to close off the connection between the water jacket B and the radiator A. I have illustrated one form of such device, which consists of a valve construction actuated by a thermostat. In this construction there is a casing 1 with an admission opening at one end, and having the laterally extending parts 2 and 3 which close off the passage-way controlled by the valve, when the valve is closed.

Projecting from the casing 1 are the supporting members 4 and 5 for supporting the thermostat, which may be of any suitable construction. As herein shown, it consists of a coil 6 of bimetal, that is of two metals, fastened together, one of which expands more than the other when heated. One end of this coil 6 is connected to a

fixed part, herein shown as a pin 7, connected with the supports 4 and 5. The other end 6a of the coil 6 is connected with the valve device so as to actuate the valve elements.

In the construction shown, the casing 1 has the two opposed discharge ports 8 and 9 which are controlled by the valve members 10 and 11. These valve members are connected together by this connecting piece 12 which extends crosswise of the casing 1. The thermostat element 6 is connected to the connecting piece 12 so as to move it and the valve members 10 and 11 when the temperature rises above a predetermined point. It will further be noted that the valve members 10 and 11 lap the edges of the ports. By this means a tight joint is formed and thereby leakage is prevented which might tend to cause the valve to open before the thermostat acts. Such action is prevented by thislapping construction, thereby insuring tight closing of the valve members, regardless of the pressure of the system, until the thermostat acts to open the valve member.

As shown in Fig. 1, the thermostat device is located in the connection D between the engine jacket B and the radiator A so as to close off this connection when the valve members are in their closed positions, that is when the engine first starts up and before the cooling liquid has become heated. The thermostat 6 is in position to come in contact with the cooling liquid in the engine jacket, and when the engine starts up the cooling liquid is held in the engine jacket until the engine heats up the proper amount, and then the valve members are opened by the thermostat and then the cooling liquid is circulated through the radiator and back through the engine jacket so as to properly cool the engine.

It will be noted that one of the valve members 10 is on the outside of the valve casing 1, and the other valve member 11 is inside the valve casing. When the valve members are closed, the pressure of the liquid inside the casing is substantially equal on the two valve members and is therefore substantially balanced so that the thermostat has no pressure to overcome when it starts to open the valve members. When the valve members 10 and 11 are partially open or fully open, this balanced condition is changed, for while substantially all the liquid flowing out of the casing through the port 8 strikes the outside valve member 10, this is not the case with the inside valve member 11, as some of the liquid flows out between it and the wall of the casing containing the port 9. Less pressure is therefore exerted on the inside valve member 11 than upon the outside valve 55

member 10, and these pressures thus become unbalanced.

Some suitable means is provided for evening up the pressures exerted on the two valve members 10 and 11 when they are partially or wholly open so as to maintain the balanced pressure condition at all times. This result is secured in the construction herein illustrated by providing an auxiliary pressure surface for the inside valve member 11, of the proper amount to cause the pressure on the valve member 11 and the auxiliary pressure surface, to be substantially equal to the pressure on the valve member 10.

As herein shown there is provided an auxiliary pressure surface 16 on the outside of the casing, against which the liquid, flowing between the valve member 11 and the port 9, strikes. This auxiliary pressure surface is so proportioned that the liquid pressure on it, plus the liquid pressure 15 on the inner face of the valve member 11, is substantially equal to the liquid pressure on the inner face of the valve member 10. This construction, therefore, maintains a substantially balanced pressure condition for the two valve members 10 20 and 11 throughout all their different positions, so that the thermostat is not required to overcome liquid pressure in moving the valve members. It will further be seen that the pressure of the liquid, due to the pump when the engine 25 is started up, has no tendency to open the valve members, and the thermostat does not, therefore, have to exert any force to hold the valve members closed when the engine is started up. It will therefore be seen that this load is removed 30 from the thermostat and that all the power the thermostat is required to utilize is simply that required to move the two valve members and associated parts. This construction, therefore, insures the proper control of the valve members. 35 It also renders the thermostat entirely independent of the presence of the liquid when the valve members are closed and makes its action solely depend on variation in temperature. With a given thermostat, therefore, the valve members 40 will be opened at the same temperature of the liquid, regardless of whether the pressure of the liquid is high or low.

The thermostat is in a position where it is contacted by the liquid before it enters the radiator, and this liquid, when the valve members 45 are opened, passes from the connection C through the valve casing, out through the ports into the radiator. There is a bypass 18 which leads from the connection C to the connection 19, which 50 connects the bottom of the radiator with the water jacket B. This bypass is a valveless bypass. It has an open end 20 which faces in the direction the water is flowing through the connection C, as clearly shown in Fig. 1, so that 55 as the water flows through the connection C to the radiator, it flows past this open end and has a Venturi action which tends to draw the water out of the bypass and prevents the water from passing down through the bypass. The lower 60 end of the bypass may enter the connection 19 and may be provided with a bent end 21, as shown in Fig. 1, which faces toward the radiator, or it may simply enter the connection 19 in a straight manner, as shown in Fig. 3.

70 The space in the connection C surrounding the end 20 of the bypass is of sufficient size so that the water flowing past the end of the bypass will prevent the water from entering the bypass and moving down through it. This can be easily 75 accomplished in most constructions. If it is

necessary to have additional means for preventing the water from passing down through the bypass 18, the construction shown in Fig. 1, with the lower end 21 bent toward the radiator, may be used, so that the water flowing from the radiator to the engine water jacket will tend to flow into the lower end of the bypass and act to prevent water from flowing out of it. In this construction, when the engine first starts up, the connection between the water jacket and radiator 10 is closed by the valve members, and the circulation of the cooling liquid is from the upper part of the water jacket through the bypass, through the lower part of the water jacket. This circulation may be produced, for example, by the 15 pump 22, or it may be produced by syphonic action if desired.

When the engine liquid heats up to a predetermined amount, the thermostat opens and the valve members 10 and 11 are opened and the 20 water then circulates from the engine jacket to the connection C and through the ports of the valve casing into the radiator, and down through the radiator, and then through the connection 19 to the bottom of the water jacket and back up 25 through the water jacket and then through the radiator, the circulation being continuous. The circulation of the liquid past the upper end 20 of the bypass now prevents the water from passing down through the bypass, and hence the bypass 30 becomes ineffective without having any valve mechanism of any kind in it, such bypass ceasing to act while the liquid is circulating through the radiator.

In Fig. 4 I have shown a modified construction 35 wherein there is located at the upper end of the water jacket B the section 23 which communicates at its bottom with the engine water jacket and which is provided with a Venturi construction comprising the part 24 which converges from the bottom toward the top and which has the discharge opening 25 which discharges 40 into the chamber 26, which forms the mouth or upper end of the bypass and which is connected to the conduit 27. The chamber 26 is 45 connected with the member 28 of the connecting section 29 leading to the radiator A. The connection between the chamber 26 and the section 28, when the engine is first started up, is closed by the thermostatic control valve in 50 the casing 1, which valve may be of any suitable construction but is illustrated as of the construction shown in Fig. 1.

The chamber 26 is a part of or connected with 55 a bypass around the radiator A, that is a bypass from the upper part of the engine water jacket B to a lower part thereof. This bypass, as shown in Fig. 4, consists of the conduit 27 which is connected to the conduit 30 which in turn is connected to the jacket B of the engine, 60 as shown at 31. This connection, in the particular instance, is made through the pump 32, although a different arrangement may be used. A connection 33 leads to the bottom of the 65 radiator A.

When the engine first starts up the valve in 70 the valve casing 1 is closed, closing the connection 29 to the radiator. The liquid passes through the part 24 into the chamber 26, then circulated through the bypass 27, 30 and 31 75 and does not pass through the radiator. When the engine becomes heated, the thermostat 6 opens the valve in the casing 1 and opens the connection to the top of the radiator A. The liquid then circulates through the connection 75

29 to the radiator A and then through the connection 33 back to the engine jacket. When the valve controlling the connection 29 is open the liquid passes through the part 24 which acts as a venturi, and by this Venturi action prevents the liquid from passing through the bypass, that is through the connections 27 and 30. It will thus be seen that there is here a valveless bypass which is rendered inoperative by the Venturi action of the liquid passing the end thereof.

I claim:

1. A circulating system for internal combustion engines, comprising an engine having a water jacket, a radiator, a connection between the upper portion of the water jacket and the radiator, a valve device for controlling the connection between the upper part of the water jacket and the radiator, and a valveless bypass extending from the upper part of the water jacket to the lower part thereof, said bypass having an upper open end which faces in the direction the water is traveling from the water jacket to the radiator, said water surrounding said bent end and traveling longitudinally therealong, which bypass acts as a bypass when the connection to the radiator is closed, and which ceases to act as a bypass when the connection to the radiator is opened.

2. A circulating system for internal combustion engines comprising a water jacket, a radi-

ator, a connection between the water jacket and the radiator, a bypass for the water jacket around the radiator, said bypass having a free passageway therethrough, said bypass having its upper end bent so as to project toward the radiator so that the water flowing from the water jacket to the radiator flows past said bent end, said bypass having its lower end bent so as to project toward the radiator.

3. A circulatory system for internal combustion engines, comprising a pipe leading from the water jacket of the engine to the radiator, including a hose section, a bypass for bypassing the cooling liquid around the radiator, said bypass having a free passageway therethrough and projecting through the wall of said hose section and having one end bent so as to project toward the radiator.

4. A circulatory system for internal combustion engines comprising an engine having a water jacket, a radiator, a connection between the upper part of the water jacket and the radiator, a valve device for controlling the said connection, a valveless bypass extending from the upper part of the water jacket to the lower part thereof, the upper end of the bypass being positioned in the path of the liquid flowing to the radiator so as to be surrounded by the liquid and having an open end facing toward the radiator.

30
